(57) **CLAIM**

The ornamental design for a blunt end pet bed with overlay, as shown and described.

DESCRIPTION

This application claims the benefit and priority of U.S. patent application Ser. No. 11/601,902, filed Nov. 20, 2006 entitled “Pet Bed Overlay, System, and Retrofit Kit”, which is incorporated by reference thereto in their entirety, as though fully set forth herein.

FIG. 1 is a top perspective view of a blunt end pet bed with overlay showing my new design;

FIG. 2 is a right side elevational view; and,

FIG. 3 is a front side view.
